UNITED STATES PATENT OFFICE.

THOS. S. SEABURY, OF STONY BROOK, NEW YORK, ASSIGNOR TO R. B. GORSUCH, OF NEW YORK, N. Y.

PIANOFORTE-ACTION.

Specification of Letters Patent No. 25,919, dated October 25, 1859.

To all whom it may concern:

Be it known that I, THOMAS S. SEABURY, of Stony Brook, in the county of Suffolk and State of New York, have invented a new 5 and Improved Pianoforte-Action; and I do hereby declare that the following is a full, clear, and exact description of the same, reference being had to the accompanying drawings, forming part of this specification, in 10 which—

Figures 1 and 2 are side views of my action, Fig. 1 exhibiting it at rest, and Fig. 2, as being checked after the hammer has struck and fallen away from the string.

15 Similar letters of reference indicate corresponding parts in both figures.

The principal object of my invention is to allow each or any one of the hammers of a piano-forte action and all the moving parts 20 pertaining to it to be removed from the instrument along with its respective key for the purpose of examination, adjustment or repair of the parts without disturbing any of the other keys or hammers or other parts 25 of the action.

With this end in view, the nature of my invention consists in pivoting the hammer butt to a post or its equivalent that is carried by the key; also in a certain mode of applying and effecting the operation of a jack or 30 fly-lever through which the blow of the hammer is produced, and in a certain mode of applying the check.

To enable others skilled in the art to make 35 and use my invention I will proceed to describe its construction and operation.

The key A, is applied in the usual manner to work on an upright pin a. At a suitable distance behind the pin a, there is erected, 40 ed upon the key, the post C, to which the butt b, of the hammer D, is pivoted by a pin c. The hammer is represented as being arranged with its head toward the rear of the key, but this position might be reversed, 45 such reversal, however, involving the necessity of reversing the positions of the other operating parts of the action. The butt b, is extended some distance in front of the post C, to receive a pivot d, by which what 50 may be termed a suspended jack or more properly a fly-lever E, is attached to it. This fly-lever passes through a slot i, provided for it in the key, and extends some distance below the key and is provided below 55 the key in its front side, with a notch e, which operates in combination with the

lower front edge of a stationary rail F, to produce the blow of the hammer when the key is struck or depressed at its front end, as will be presently described. A spring h, 60 is applied within the slot i, in front of the fly-lever, to press the latter toward the said rail F. The said rail F, extends the whole width of the action, that is to say, under all the keys. Its operating edge is covered with 65 leather, and so the back of the notch is faced with felt. The regulating screw G, screws obliquely through the fly-lever E, and acts in combination with an inclined plane f, formed on the back of the post C. The 70 check consists of a small block H, attached to the bottom of the key in front of the fly-lever, and having its back beveled or curved to fit a corresponding beveled or curved face g, formed in the front of the lower part of 75 the fly-lever. The check is faced with cloth or leather. The hammer rest consists of a block I, secured upon the top of the key.

The operation of the action is as follows: When the front end of the key is struck or 80 depressed by the player the part in rear of the pin a, rises, but as the fly-lever is prevented rising by its notch catching under the rail F, it holds down the front portion of the hammer butt, while the post C, and pivot 85 c, rise, and the hammer head is thrown sharply upward against the string. As the hammer completes its stroke, the fly-lever is pushed from the rail F, by the wedge like action of the face f, of the post C, on the 90 regulating screw G, and the hammer liberated, but before the latter can fall farther than is necessary to free itself from the spring, the inclined face g, of the fly-lever comes in contact with the check H, and 95 hence its further descent is prevented; but it is only necessary to permit the front end of the key to rise a very little way, for the notch of the fly-lever to slip under the rail F, again, and bring the action to a condition 100 for repeating the blow of the hammer.

To remove a key with its respective hammer, and the working parts pertaining thereto from the piano-forte, it is only necessary to take out the part of the case commonly 105 known as the name-board, and to raise the key at the front end high enough to permit it to pass over the pin a, and then to draw it forward, when it brings with it the hammer, the fly-lever, the check and the hammer rest. 110

This action besides enabling each or any one of the hammers and all the moving parts

pertaining to the hammer and key to be withdrawn from the instrument along with the key, possesses several advantages over most of the actions in common use, viz: 5 First, it is capable of repeating with greater facility; second, it is of more simple construction; third, the force applied to the key is transmitted in a more direct manner to the hammer; fourth, it has a more expressive touch; fifth, the hammer is effectively prevented "sticking up" in case of dampness and swelling of the parts; and sixth, the inconvenience arising from what is called in the French action, short jacks, is 10 entirely obviated.

What I claim as my invention, and desire to secure by Letters Patent, is:—

1. Pivoting the hammer butt to a post, or its equivalent, carried by its respective key, 20 substantially as herein specified, for the purpose of enabling it to be withdrawn from the instrument along with the key.

2. The suspended jack or fly-lever E, at-

tached to the hammer butt, and provided with a notch e, operating in combination 25 with a stationary rail F, substantially as herein described.

3. The arrangement of the regulating screw in the suspended jack or fly-lever in combination with the inclined plane f, on 30 the post erected upon the key to carry the hammer, substantially as herein described; but I wish to be understood as not claiming generally either the placing of the regulating screw in the jack, or the employment of 35 an inclined plane or wedge to act in combination with an inclined or wedge-like surface.

4. The check H, applied to the bottom of the key and operating in combination with 40 the suspended jack or fly-lever, substantially as herein described.

THOS. S. SEABURY.
